UNITED STATES PATENT OFFICE

130,779

DESIGN FOR A WHEEL DISK

Frederic P. Plotkin, Los Angeles, Calif.

Application May 26, 1941, Serial No. 101,150

Term of patent 14 years

To all whom it may concern:

Be it known that I, Frederic P. Plotkin, a citizen of the United States, residing at Los Angeles, in the county of Los Angeles and State of California, have invented a new, original, and ornamental Design for a Wheel Disk, of which the following is a specification, reference being had to the accompanying drawing, forming part thereof.

Figure 1 is a side elevational view of a wheel disk showing my new design.

Figure 2 is an end elevational view of the wheel disk shown in Figure 1.

I claim:

The ornamental design for a wheel disk, as shown.

FREDERIC P. PLOTKIN.
